UNITED STATES PATENT OFFICE.

EUGEN TÜRCK, OF LANGERFELD, NEAR BARMEN, GERMANY.

PROCESS FOR THE MANUFACTURE OF LACE WITH A GAUZELIKE GROUND.

Application filed July 31, 1916. Serial No. 112,455.

To all whom it may concern:

Be it known that I, EUGEN TÜRCK, a subject of the Emperor of Germany, and resident of Langerfeld, near Barmen, Rhenish Prussia, Germany, have invented a new and useful Process for the Manufacture of Lace with a Gauzelike Ground (for which I have filed applications for patent in Germany Jan. 9, 1915, Patent No. 294217, and 5 March 5, 1915, Patent No. 295161; Switzerland Nov. 1, 1915, Patent No. 72814; Austria Nov. 2, 1915, Patent No. 73814; Sweden Nov. 3, 1915, Patent No. 41390; Netherlands Nov. 8, 1915, Patent No. 2783; Belgium Nov. 15 8, 1915, Patent No. 270629; France Nov. 13, 1915, Patent No. 512098; England Jan. 7, 1916, Patent No. 100015; Italy April 10, 1916, Patent No. 153776; Spain April 26, 1916, Patent No. 62162), of which the following is a full, clear, and exact specification, such as will enable others skilled in the art of this manufacture to make and use the same.

Laces with a gauze-like ground are already 25 known, and these have been manufactured on single-thread braiding machines (i. e. machines with one bobbin per plate) in such a manner that the braiding threads are braided together in groups into the several narrow strips which run longitudinally and form the warp or chain, and these strips are connected at certain places to form transverse weft strips by exchanging the marginal threads of each two adjacent longitudinal strips. These laces have come into 30 the market hitherto almost exclusively as so-called insertions, that is, with straight edges.

The subject-matter of the present invention 40 is a new process for manufacturing such bobbin-made lace with a gauze-like ground on single-thread braiding machines, which process makes it possible to produce pretty and permanent scalloped or serrated formations. This process consists in the following.

During the manufacture of the lace on the single-thread braiding machine one or more retaining threads are worked into the lace in such a manner that these threads 45 are braided, in accordance with the form of the serrations or scallops to be produced, alternately in a longitudinal strip and in a

transverse strip, and then the lace is cut out along the retaining threads. In this way is obtained a lace with an edge having serrated or scalloped formations, which edge owing to said retaining threads, which run the entire length of the web and therefore always lie along the edge, is entirely protected against fraying out, notwithstanding 55 that some of the bobbin-threads have been cut through. Perishing of this lace through use and in washing is not therefore to be feared. The serrated and scalloped formations however have exactly the 60 same style as the remainder of the web, that is, like the latter they are part of the lace formation.

If more of such retaining threads are introduced into the fabric then the same are 70 disposed in the weft and warp strips and not only interlaced with the ordinary bobbin strands but also with each other in order to increase the durability of the 75 margin.

In manufacturing narrow laces, two are 80 preferably produced simultaneously on the lace machine in such manner that the same are braided with their serrated or scalloped formations engaging one another, there being then of course for each lace a thread worked in therewith in the above-described manner. This entirely avoids waste when the lace is cut out. The invention further 85 consists in the lace produced as above.

Two examples of a lace manufactured according to my invention are illustrated in the accompanying drawings, wherein show:—

Fig. 1 is a plan view of the lace fabric 90 with the two parts united,

Fig. 2 shows the same after cutting to form two serrated parts,

Fig. 3 is a detail of the structure shown in Fig. 1, on an enlarged scale,

Fig. 4 is a plan view of a lace produced 95 in a somewhat modified process,

Fig. 5 is a detail of the lace shown in Fig. 4, on an enlarged scale.

Referring to the drawing, Figures 1-3 100 show the edge of the lace is secured by means of one special retaining thread. In this example the longitudinal or warp strips α of the gauze-like lace each consist of four

threads 1, 2, 3, 4 braided together, and the transverse strips *b* are formed owing to the exchange at certain places of the marginal threads of two adjacent longitudinal strips *a*. A pattern may be produced by an accumulation of transverse strips, i. e. by filling in the various squares by a more frequent exchange of the braiding threads. The web shown in Figs. 1 and 3 for manufacture on a single-thread braiding machine forms indeed an intermediate product for obtaining the two laces. Accordingly, the two retaining threads *c* and *d* are worked into this intermediate product, the manner 15 of interworking being clearly shown in Fig. 3. These threads engage at one time the longitudinal strips *a*, and then they pass with the transverse strips to the next longitudinal strips. By cutting through the 20 intermediate product shown in Figs. 1 and 3 between the two retaining threads, i. e. along the dotted line A—B, the two finished laces shown in Fig. 2 are obtained. In these the specially incorporated threads *c*, *d* run 25 along the edge which is here of serrated formation. These threads are at no place severed, and everywhere give the serrations a secure hold, and so with certainty prevent the said edge from being frayed out or un- 30 ravelled. In the example those squares or rectangles of the gauze like lace which are located alongside the serrated edge are filled in. This is however not at all necessary. These portions may remain open if desired. 35 Moreover in the present case the longitudinal strips *a* consist wholly of four braiding threads and the threads *c* and *d* are specially inserted.

In Figs. 4 and 5 is disclosed a modified 40 method of my invention according to which I again employ the four braiding threads 1, 2, 3 and 4 as shown in order to constitute the longitudinal or warp strips *e*, the transverse strips *f* being formed as before described by exchanging the marginal strands of two adjacent strips *e*. Beside in the said fabric are interwoven some other threads *g* running in zig-zag form as shown and being partly connected with the longitudinal 45 strips *e* and partly with the horizontal or weft strips *f*, so that the ground of the fabric has an appearance of the so called, "fillet antique."

To secure the serrated margin against 55 fraying I have worked in the lace during its manufacture on the single thread braiding machine the four threads *h*, *i*, *k*, *l* in a manner that they are introduced in a marginal longitudinal strip *e*, then made into 60 a weft strip *f* where they interlace with the strands *g* and then worked again into the next adjacent warp strip *e*. As will be clearly understood from Figure 5 the threads *h*, *i*, *k*, *l* are braided with each other and 65 with the ordinary bobbin threads 1, 2, 3, 4.

The fabric is also in this example cut out along the retaining threads, the braiding threads which are cut off being so strongly interwoven that fraying out is entirely avoided. Of course, in the example shown 70 in Figs. 4 and 5 also two laces may be manufactured simultaneously in a similar manner as described in connection with Figs. 1 to 3.

On using a plurality of retaining threads for each lace, as in Figs. 4 and 5, I prefer 75 to constitute the weft portions *x* at the edge of the lace exclusively by the retaining threads *h*, *i*, *k*, *l*, simplifying thereby the manufacture, the braiding threads 1 to 4 which afterwards are to be cut through need 80 not to be interchanged at the edge of the lace, the retaining threads forming as shown specially in Fig. 5 a continuous braid along the margin.

What I desire to secure by Letters Pat- 85 ent is:

1. The improved process of manufacturing a lace with gauze-like ground and scalloped or serrated edge on a single-thread lace braiding machine which consists in the formation of a plurality of warp strips, each consisting of a number of braiding threads, connecting the adjacent warp strips by interchanging some of the threads of said strips to form a plurality of weft strips, working in one or more retaining threads, said retaining threads running alternately in the direction of the warp strips and of the weft strips, and then cutting out 95 the lace along the said retaining thread or 100 threads.

2. The improved process of simultaneously manufacturing two laces with gauze-like ground and scalloped or serrated edge on a single-thread lace braiding machine 105 which consists in the formation of a plurality of warp strips, each consisting of a number of braiding threads, connecting the adjacent warp strips by interchanging some of the threads of said strips to form a plurality of weft strips, working in two retaining threads or two groups of retaining threads, said two retaining threads or 110 groups of retaining threads running, one independently from the other, alternately 115 in the direction of the warp strips and of the weft strips, and then cutting out the laces between the said two retaining threads or groups of retaining threads.

3. The improved process of manufacturing 120 a lace with gauze-like ground and scalloped or serrated edge on a single-thread lace braiding machine which consists in the formation of a plurality of warp strips, each consisting of a number of braiding threads, 125 connecting the adjacent warp strips by interchanging some of the threads of said strips to form in the interior of the lace a plurality of weft strips, interbraiding a plurality of retaining threads, said retaining 130

threads running alternately in the direction of the warp strips and of the weft strips, forming the weft strips at the edge of the lace exclusively by the said retaining threads, and then cutting out the lace along the said retaining threads.

In witness whereof I have signed my

name in the presence of two subscribing witnesses.

EUGEN TÜRCK. [L.S.]
